UNITED STATES PATENT OFFICE.

JAN WOREK, OF CHICAGO HEIGHTS, ILLINOIS, ASSIGNOR OF ONE-HALF TO FRANK FLOREK, OF CHICAGO HEIGHTS, ILLINOIS.

WIRE-CUTTER.

1,277,521.

Specification of Letters Patent. Patented Sept. 3, 1918.

Application filed June 20, 1918. Serial No. 240,934.

To all whom it may concern:

Be it known that I, JAN WOREK, a subject of the Emperor of Austria, having declared my intention to become a citizen of the United States of America, residing at Chicago Heights, in the county of Cook and State of Illinois, have invented certain new and useful Improvements in Wire-Cutters, of which the following is a specification.

10 The primary object of the invention is the provision of a wire cutter employed with knives or bayonets whereby barbed and similar wires may be quickly severed while the blade upon which the device is mounted is capable of all ordinary uses for which the same is intended.

15 A further object of the invention is to provide a device adapted for cutting through barbed wire entanglements, the structure possessing great strength and being operated in conjunction with a blade upon which the device is mounted, the structure being cheaply and easily manufactured.

20 25 In the drawings forming a part of this application and in which like designating characters refer to corresponding parts throughout the several views,

Figure 1 is a side elevation of a knife carried by a rifle barrel and provided with my device, a wire being shown in section in position for cutting;

Fig. 2 is an elevational view of the opposite side thereof;

30 35 Fig. 3 is a plan view of the same looking toward the top of the barrel with the muzzle portion thereof broken away and a wire illustrated in position for cutting;

40 45 Figs. 4 and 5 are transverse sectional views taken upon lines IV—IV and V—V, respectively, of Fig. 1; and

Fig. 6 is a detail view, partly in section, of the device.

It being understood that my wire cutter 50 55 may be operatively mounted upon any form of blade, the same is herein illustrated in connection with a knife or blade 10 having a handle 11 secured by means of split double collars 12 and 13 to the muzzle portion of a rifle barrel 14 with the blade 10 projecting forwardly thereof for employment as a bayonet.

The knife handle 11 is secured beneath the barrel 14 opposite the sight 15 of the

rifle while the lower edge 16 of the blade 10 55 is the sharpened cutting portion thereof. A cutting jaw 17 has its shank 18 pivoted to the blade 10 by means of a rivet 19 in such a manner that the cutting edge 20 of the said jaw coöperates with the edge 16 of 60 the blade 10 in cutting wires such as 21, positioned between the jaw and blade. A leaf spring 22 is secured to the shank 18 and bears upon the adjacent shoulder 23 at the inner end of the handle 11 for normally 65 maintaining the jaw 17 away from the said blade 10.

A substantially right angular operating lever 24 is pivoted by means of the rivet 19 upon the opposite side of the blade 10 from 70 the jaw 17, while a rocker 25 is pivoted as at 26 to the handle 11 and is connected by means of similar links 27 and 28 with the jaw shank 18 and lever 24 respectively.

The lever 24 has its free end portion or 75 arm 29 provided with a broad curved inner face 30 adapted for engaging the wire 21 between the face 30 and the blade edge 16 when the device is applied to the wire for cutting the same. The arm 29 is of greater 80 length than the jaw 17 while the link 27 of the jaw is of greater length than the link 28 of the lever 24 and the spring 22 is so positioned relatively of the pivot point of the jaw 17 as to normally maintain the lever 85 24 arm 29 extending in advance of the jaw 17 toward the pointed end 31 of the blade 10 and with the jaw edge 20 inoperatively spaced from the blade edge 16.

The soldier in charge of the rifle positions the blade edge 16 upon the wire 21 and upon forcing the device forwardly contacts the curved face 30 of the lever 24 with the wire which shifts the lever 24 and jaw shank 18 upon the pivoting rivet 19 and which 90 movement of the jaw and lever are in opposite directions by reason of the rocker 25 and the connecting links. The forward thrust of the barrel 14 forces the lever arm 29 outwardly and rearwardly permitting the 100 blade edge 16 to slide upon the wire 21 whereby the curved face 30 of the lever 24 forces the jaw 17 inwardly engaging the edge 20 thereof with the wire which is thereby forcibly severed between the jaw 105 edge 20 and the knife edge 16. After the operation of the device, the spring 22 returns the members to their normal positions

with the jaw 17 retracted and the lever arm 29 in its operative position ready for contacting another wire for cutting the same.

What I claim as new is:—

- 5 1. A wire cutter for knives and the like comprising in combination with a blade, a cutting jaw adapted for coöperating with the cutting edge of the blade pivoted to the blade, an operating lever for the jaw pivoted to the opposite side of the blade, and connections between the said jaw and lever whereby the movement of the lever is adapted for shifting the jaw in an opposite direction and normal positioning means for the 15 jaw and lever.
- 10 2. In combination with a knife having a handle and a blade, an angular lever and a jaw pivotally mounted upon opposite sides of the blade, a rocker pivoted to the handle, link connections between the opposite ends of the rocker and the adjacent ends of the jaw and lever whereby a pressure upon the lever toward the handle is adapted for shifting the jaw toward the edge of the blade in 25 the cutting operation.
- 15 3. In combination with a knife having a handle and a blade, an angular lever and a jaw pivotally mounted upon opposite sides of the blade, a rocker pivoted to the handle, link connections between the opposite ends of the rocker and the adjacent ends of the jaw and lever whereby a pressure upon the lever toward the handle is adapted for shifting the jaw toward the edge of the blade in 25

the cutting operation, the link between the 35 rocker and jaw being of greater length than the connection between the rocker and lever, and a positioning spring carried by the jaw engaging the adjacent portion of the handle whereby the jaw is normally maintained 40 open with the lever positioned in advance of the jaw adapted for engaging the work.

4. A device of the class described comprising in combination with a rifle barrel, a knife handle secured to the barrel, a blade 45 projecting from the handle having a cutting edge at the side thereof opposite the barrel, a jaw having an angularly extending shank pivoted to one side of the blade, the said jaw having a cutting edge adapted for coöperation 50 with the edge of the blade, an angular lever pivoted to the opposite side of the blade from said shank having an arm normally extending in advance of the jaw toward the free end of the blade and provided with a curved inner face adapted for forcibly 55 engaging a wire to be cut, a rocker pivoted to the handle, links of unequal length connected between the opposite ends of the rocker and the adjacent ends of said shank and lever, and a normal positioning spring carried by the jaw engaging the adjacent portion of the handle whereby the jaw is normally maintained in spaced relation with respect to the cutting edge of the blade.

In testimony whereof I affix my signature.

JAN WOREK.
